PULLING JACK.

FILED JUNE 16, 1921.

2 SHEETS—SHEET 2.

UNITED STATES PATENT OFFICE.

FRANCIS F. WILSON, OF HOLLISTER, CALIFORNIA.

PULLING JACK.

Application filed June 16, 1921. Serial No. 478,160.

To all whom it may concern:

Be it known that I, FRANCIS F. WILSON, a citizen of the United States, residing in Hollister, county of San Benito, and State of California, have invented a new and useful Improvement in a Pulling Jack, of which the following is a specification.

My invention relates to improvements in a jack provided with an elongated ratchet bar arranged to move an object by a direct pressure, or by a tension created in a connecting member.

The primary object of my invention is to provide an improved jack adapted for applying either pressure or tension.

Another object is to provide improved securing means facilitating the anchoring of a jack.

A further object is to provide improved means engaging a connection to an object to be moved to facilitate the movement of said object by means of a pulling force applied through said connection.

A further object is to provide an improved jack of the character described arranged to give an increased range of movement.

A still further object is to provide a simplified construction adapted to be manufactured at a reduced cost.

I accomplish these and other objects by means of the device disclosed in the drawings forming a part of the present specification wherein like characters of reference are used to designate similar parts throughout said specification and drawings, and in which:

Fig. 1 is a broken side elevation partly in section of my improved jack.

Fig. 2 is a broken plan view of my invention upon a larger scale, disclosing the anchoring chains secured thereto.

Fig. 3 is a view disclosing the application of my jack in pulling a vehicle.

Fig. 4 is a view illustrating the utility of my invention in lifting the forward end of a vehicle by tension created in a connecting member.

Fig. 5 is a view disclosing the lifting of a wheel upon a vehicle by direct pressure; and

Fig. 6 is a broken detail of the clutch mounted upon the ratchet bar.

Referring to the drawings the numeral 1

is used to designate in general a housing having a notch 2 formed in the one edge thereof, and provided with an outwardly extending lip 3 arranged to engage any convenient portion of an object to be moved by direct pressure in a manner hereinafter described.

A bar 4 formed preferably from channel iron extends longitudinally through the housing 1, the tops of the channel flanges being provided with ratchet teeth 6 as best disclosed in Fig. 1 of the drawings. The bar 4 may be made of any desired length to permit a range of movement suited to the individual requirements of the user.

A pair of pawls 7 and 8 are mounted within the housing 1 in operative engagement with the ratchet teeth 6 upon an operating lever socket 9 pivotally mounted within the housing 1. An operating lever 11 is removably engaged by the socket 9 to afford a suitable leverage for operation of the pawls.

A spring 12 is mounted between the pawls 7 and 8 to hold the same in operative engagement with the teeth 6, the pawl 7 being moved by the lever socket 9 to engage successive teeth 6 for advancing the bar 4 through the housing 1, and the pawl 8 being held in engagement with successive teeth 6 to prevent backward movement of the bar 4 when the pawl 7 is moved to engage each succeeding tooth. A lever 13 provided with an extending lug 14 is pivotally mounted upon the housing 1 adjacent the spring 12. The lug 14 normally depresses the spring 12 to hold the pawls 7 and 8 in operative position as above described, as shown in full lines in Fig. 1. The lever 13 extends outwardly through a slot 16 in the housing 1 and may be moved to the position shown in dotted lines to release the spring 12, thereby permitting the pawls 7 and 8 to disengage the ratchet teeth 6 to permit the bar 4 to be moved through the housing independently of the pawls.

Cleats 17 having outwardly turned ends 18 are secured upon the sides of the housing 1, one of said cleats 17 having one end of a chain 19 secured thereto, and the other cleat 17 being provided with a hook 21 adapted to engage a link in the chain 19 in a manner hereinafter more fully described.

One end of the bar 4 is provided with

a lug 22 upon which is pivotally mounted a clutch member 23 having an eccentric serrated surface 24 arranged to engage a wire 26 or other connecting member and hold the same rigidly against the bar 4 as shown in Fig. 6 of the drawings, an increase in tension in the connection 26 causing the same to be more firmly gripped by the member 23. A hook 27 may be formed upon 10 the member 23 to engage a chain or other connection not suited for engagement between the surface 24 and the bar 4. A suitable link 28 or clevis may also be mounted at the end of the bar 4 to further facilitate the attaching of a connection 26 to the bar.

The other end of the bar 4 is provided with a shoe 29 removably secured to the bar by a pin 31, the shoe 29 providing a bearing surface to rest upon the ground to permit an object to be raised by direct pressure as hereafter described.

My invention is designed primarily for exerting a pulling force upon an object to be moved, the application of my device for pulling a vehicle 30 out of a mud hole or the like being illustrated in Fig. 3 of the drawings. The operation of my invention in this connection is as follows:

30 The housing 1 is anchored to a fixed object such as a stake 32 driven into the ground a suitable distance in advance of the vehicle, or to any convenient post or tree should either be at hand, by making a loop of the 35 chain 19 from the cleat 17, to which the chain is permanently secured, around the stake 32 or other fixed object, the chain 19 being brought back through the notch 3 and a second loop made about the stake 32, the 40 free end of the chain being then brought into engagement with the hook 21. In this manner the housing 1 is anchored from two longitudinally spaced points thereby holding the bar 4 in the line of pull and preventing oscillation of the housing 1 when the lever 11 is moved to operate the pawls 7 and 8. A wire 26, is secured upon the 45 frame of the vehicle in any convenient manner and the free end of the wire 26 brought into engagement with the clutch member 23 as above described. The lever 11 may now be oscillated to cause the pawl 7 to engage successive teeth 6 and advance the bar 4 longitudinally through the housing 1, in this manner creating a tension in the wire 24 and causing a pulling force to be exerted 50 upon the vehicle.

It sometimes happens that the front 60 wheels of a vehicle become mired in a mud hole in such a manner that a footing cannot be had for the application of a jack in the usual manner. In this event, my improved device may be connected in the usual manner above described to a beam 33 suitably supported above the portion of the vehicle

to be raised as illustrated in Fig. 4 of the drawings. Movement of the bar 4 through the housing 1 anchored in this fashion will pull the vehicle upwardly to the desired elevation.

Fig. 5 of the drawings illustrates the manner in which a wheel of a vehicle may be lifted by a direct pressure in the usual manner. In this case, the shoe 29 is applied to the end of the bar 4 to rest upon the ground or other supporting surface. The housing 1 is now advanced along the bar 4 until the lip 3 is brought into engagement with a rigid portion of the vehicle such as the axle 33. Operation of the pawls 7 and 8 by the lever 11 will now operate to move the housing 1 relatively to the bar 4 which is rigidly supported upon the ground, thereby causing the lip 3 to move the vehicle upwardly a corresponding amount.

While I have illustrated my invention in reference to its utility for lifting and moving a vehicle, the device is equally useful for moving any other heavy object, the operation being entirely analogous. My invention is particularly useful as a means for stretching wire for fences and the like. In this connection, the housing 1 is anchored to a fence post in the manner above described and the wire stretched to the desired tautness and stapled or otherwise secured to the post.

Having thus described my invention what I claim as new and desire to secure by Letters Patent is:

1. A jack comprising a housing; a ratchet bar extending longitudinally through said housing; pawls mounted within the housing in operative engagement with the ratchet bar; means for operating said pawls to move the bar through the housing; chain engaging cleats mounted upon the sides of the housing; a chain permanently secured at one end to one of the cleats and adjustably secured at the other end thereof to the other cleat for anchoring said housing to a fixed object; and means mounted upon one end of the ratchet bar to engage a connection to an object to be moved whereby movement of the bar through the housing operates to exert a pulling force upon said object to be moved.

2. A jack comprising a housing; a ratchet bar extending longitudinally through said housing; pawls mounted within the housing in operative engagement with the ratchet bar; means for operating said pawls to move the bar through the housing; chain engaging cleats secured upon the sides of the housing; a chain permanently secured at one end to one of the cleats; a hook secured upon the other cleat to adjustably engage the other end of the chain for anchoring said housing to a fixed object; and a clutch mounted upon one end of the ratchet bar to engage a connection to an object to be moved whereby

movement of the bar through the housing operates to exert a pulling force upon the object to be moved.

3. A jack comprising a housing; a ratchet bar extending longitudinally through said housing; pawls mounted within the housing in operative engagement with the ratchet bar; means for operating said pawls to move the bar through the housing; chain engaging cleats secured upon the sides of the housing; a chain permanently secured at one end to one of the cleats; a hook secured upon the other cleat to adjustably engage the other end of the chain for anchoring said housing to a fixed object; a clutch mounted upon one end of the ratchet bar to engage a connection to an object to be moved whereby movement of the bar through the housing operates to exert a pulling force upon the object to be moved; a shoe mounted upon the other end of the ratchet bar to engage the ground; and laterally extending lips formed integrally with the housing to engage an object to be lifted whereby movement of said housing relatively to the bar will lift said object.

4. A jack comprising a housing having a notch formed therein; a ratchet bar extending longitudinally through said housing; pawls mounted within the housing in operative engagement with the ratchet bar; means for operating said pawls to move the bar through the housing; chain engaging means secured upon the housing; a chain permanently secured at one end and adjustably secured at the other end thereof to the chain engaging means, said chain being arranged to be looped about a fixed object and through the housing notch to engage the housing at longitudinally spaced points for anchoring the same to said fixed object; and a clutch mounted upon one end of the ratchet bar to engage a connection to an object to be moved whereby movement of the bar through the housing operates to exert a pulling force upon said object to be moved.

5. A jack comprising a housing having a notch formed therein; a channel bar extending longitudinally through said housing; ratchet teeth formed upon the tops of the channel sides; pawls mounted within the

housing in operative engagement with said ratchet teeth; means for operating said pawls to move the bar through the housing; a chain engaging means secured upon the housing; a chain permanently secured at one end and adjustably secured at the other end thereof to the chain engaging means, said chain being arranged to be looped about a fixed object and through the housing notch to engage the housing at longitudinally spaced points for anchoring the same to said fixed object; and a clutch mounted upon one end of the bar to engage a connection to an object to be moved whereby movement of the bar through the housing operates to exert a pulling force upon said object to be moved.

6. A jack comprising a housing having a notch formed therein; a channel bar extending longitudinally through said housing; ratchet teeth formed upon the tops of the channel sides; pawls mounted within the housing in operative engagement with said ratchet teeth; means for operating said pawls to move the bar through the housing; chain engaging means secured upon the housing; a chain permanently secured at one end and adjustably secured at the other end thereof to the chain engaging means, said chain being arranged to be looped about a fixed object and through the housing notch to engage the housing at longitudinally spaced points for anchoring the same to said fixed object; and a clutch mounted upon one end of the bar to engage a connection to an object to be moved whereby movement of the bar through the housing operates to exert a pulling force upon said object to be moved; a shoe mounted upon the other end of the bar to engage the ground; and a lip formed upon the housing by bending an extension upon one end of the housing to a laterally extending position to engage an object to be raised whereby operation of the pawls moves the housing relative to the bar to lift said object to be raised.

In witness whereof I hereunto set my signature.

FRANCIS F. WILSON.
